UNITED STATES PATENT OFFICE.

WILLY BEIN, OF BERLIN, GERMANY.

PROCESS OF AND APPARATUS FOR ELECTROLYZING.

SPECIFICATION forming part of Letters Patent No. 591,730, dated October 12, 1897.

Application filed June 15, 1896. Serial No. 595,681. (No model.) Patented in Germany October 22, 1893, No. 84,547; in England November 12, 1894, No. 21,838; in France July 20, 1895, No. 236,203; in Belgium July 20, 1895, No. 116,623; in Hungary October 31, 1895, No. 4,129, and in Austria May 8, 1896, No. 1,812/46.

To all whom it may concern:

Be it known that I, WILLY BEIN, doctor of philosophy, a subject of the King of Prussia, German Emperor, and a resident of Berlin, 5 in the Kingdom of Prussia, German Empire, have invented a certain new and useful Improved Process of and Apparatus for Electrolyzing, (for which I have obtained patents in Germany, No. 84,547, dated October 22, 1893; 10 in France, No. 236,203, dated July 20, 1895; in Belgium, No. 116,623, dated July 20, 1895; in Austria, No. 1,812/46, dated May 8, 1896; in Hungary, No. 4,129, dated October 31, 1895, and in England, No. 21,838, dated November 15 12, 1894,) of which the following is a full, clear, and exact description.

If an electrolytic solution is electrolyzed for a considerable time in a cell, the products of decomposition will finally gather at the 20 anode and cathode, and after this has taken place the electric energy conveyed to the solution will be lost. These products of decomposition have hitherto been separated by mechanical means—such as porous dia- 25 phragms, artificial or natural membranes, or the like—in the case of standing electrolytes. The employment of diaphragms has many advantages. In the first place, they do not entirely prevent a recombination of the products formed due to endosmotic action, as 30 pointed out by Hittorf in *Poggendorff's Annalen*. Then, again, diaphragms produce considerable resistance and render it difficult to work with simple apparatus, they are not 35 economical, and are subject to chemical and mechanical destruction.

In the electrolytic processes hitherto employed diaphragms have invariably been employed in order to enable the electrodes to be 40 arranged as close together as possible and thus to reduce the resistance, but in the best-known processes—such, for instance, as that patented to Carmichael, No. 518,710, and in fact in all processes hitherto employed—the 45 electrodes have been arranged one above the other, thus necessitating the employment of a diaphragm and involving the disadvantage that any gases which may be produced will pass through or cross the electrolytic path and 50 cause the products of decomposition to rise

into the neutral layer which intervenes between the electrodes.

According to the present invention the diaphragm is dispensed with entirely, a neutral layer or zone of the electrolytic solution being preserved and caused to act to keep the products of decomposition collecting at the electrodes separated. This neutral zone is obtained and preserved by arranging the electrodes one alongside of the other instead of 55 one above the other. The electrodes may be arranged in one and the same horizontal plane or in varying horizontal planes or in planes substantially horizontal, the main condition being that they are arranged relatively side- 60 wardly of each other. The relative vertical position of the electrodes with regard to each other depends upon the kind of salt to be decomposed, said electrodes being under all circumstances so arranged as to allow the gases, 65 if such are produced, free exit without crossing the path of the electric current.

I have found by numerous experiments that while the current is passing through the solution no practically-observable intermingling of the products of decomposition collecting at the electrodes takes place and that this is the case even in the presence of slight mechanical disturbances. The separating 75 layer or zone of non-decomposed solution will gradually decrease in bulk the longer the process is continued, but no intermingling will take place. It will thus be clear that if fresh solution is introduced into the neutral or non-decomposed zone in proportion to that 80 removed by decomposition this zone will remain constant and form a fluid-diaphragm which will serve all practical purposes and obviate the necessity of a mechanical dia- 85 phragm.

Solution is drawn off from the apparatus at the same slow rate at which it is added, being taken both from the lowest layer, which contains lye, iodin, or acid, and from the uppermost layer, consisting, for instance, of a diluted solution of potassium chlorid containing chlorin or bromin. In order to avoid any agitation or disturbance of the layers, the feed and outlet pipes are provided with spray- 95 heads or a series of rose-like pipes within the 100

apparatus, which are distributed as evenly as possible over the area of the electrodes. The closer the outlets are to the electrodes the easier will it be possible to remove without delay the concentrated or diluted layer. The removal may take place by means of overflow-siphons or the like.

When the process in a cell has been completed and it is required to stop working, the neutral zone may be allowed to decrease until it is almost on the point of vanishing, when a mechanical diaphragm may be introduced, but this is only necessary when it is required to stop working one or more of the cells.

15 A neutral zone or layer of the kind described is not formed by the processes hitherto employed, because the diffusion, or, more properly speaking, the endosmosis caused by the porous partition, gives rise to local currents which disturb the separating-layer and render it impossible to obtain a concentration equal to that obtained by the present process.

One form of carrying out the present process is illustrated in the accompanying drawings, forming part of this specification, and in which similar letters and figures of reference denote similar parts throughout the several views.

Figure 1 is a vertical cross-section through an apparatus which may be employed, and Figs. 2 and 3 are similar sections showing modified forms of the device.

The apparatus consists of a receptacle having two impervious partitions W W' extending across the same from about the top and reaching down to a short distance above the bottom and one partition W^2 extending from the bottom upward and terminating some little distance below the top, said receptacle being thus divided into four communicating compartments A, B, C, and D, through which the electric current may flow from the anode N to the cathode K without hindrance.

The two interior compartments B and C may be entirely separated one from the other by a slide E, so that the whole apparatus may be divided into two compartments A, B and C D, having no communication with each other. Such division would, however, only take place when the process of decomposition is to be stopped.

I will now proceed to give one or two instances of the application of the process, the present apparatus being employed.

55 If bromid of sodium is subjected to the electrolysis in the apparatus above described, the hydrate of soda formed at the cathode will constantly sink to the bottom of the compartment D by gravity. As soon as it gets 60 into the compartment C a separating-layer begins to form between it and the bromid of sodium not yet decomposed. Simultaneously bromin will separate out at the anode, first sinking in A and then entering and rising in 65 the compartment B, thus forming in this latter chamber a separating layer or zone of

non-decomposed solution. While the process is being continued this separating-zone of non-decomposed solution will be kept about constant by adding fresh solution to the neutral zone through the inlets o o' in the same proportion as the decomposed solution is drawn off at the cocks H and H'. If the process is to be stopped, the neutral zone should be allowed to decrease to a minimum and the 75 slide E dropped just before the products of decomposition could mix over the partition W^2 , when the products of decomposition in the chambers A B and C D may be drawn off at H H'.

In order to remove the last traces of non-decomposed solution forming the final small neutral zone, siphons may be introduced into the inlet-openings o o' , through which the upper part of the solution standing in the 85 chambers B and C and forming the neutral zone may be removed, previous to drawing off the pure products of the electrolytic decomposition.

The process may be carried out in a variety 90 of ways, the forms illustrated and described being merely instances. Thus in electrolyzing bromid of sodium, as in all cases in which the products of decomposition are heavier specifically than the electrolyte, the arrangement indicated in Fig. 2 may be employed. In this case only two partitions W and W' are employed. The anode is placed in the compartment or chamber 3 at or toward the bottom of the same, the cathode in the chamber 1 near the surface of the liquid. The bromin collects in chamber 3 and rises very slowly in the same. The soda-lye formed in chamber 1 sinks gradually to the bottom, passes into the chamber 2, and rises in the 105 same, the neutral zone being retained by adding solution at the top of the chambers 2 and 3 in the same proportion as the decomposition takes place, the decomposed products being drawn off from the lower parts of the 110 chambers 1 and 3. This arrangement of the cathodes allows the hydrogen to escape without crossing the electrolytic path, in which case it would agitate the solution and cause the layers to intermingle.

In order to mechanically separate the layers during or after the passage of the current through the solution, slides or valves E and E' may be employed. If desired, one of the resulting lyes may be placed in the apparatus 120 at the beginning of the process and a layer of indecomposed salt solution arranged above it, so that the formation of layers will be present from the beginning.

If the products of decomposition resulting 125 from the electrolysis are of different specific gravities, so that one product would rise and the other sink, as would be the case in electrolyzing potassium chlorid and cyanid of potassium, in which case chlorin and cyanogen 130 would escape as gases and the potassium lye sink to the bottom, or in electrolyzing rhod-

anid of potassium, in which case the specifically lighter sulfocyanic acid would rise and the potassium lye sink, the present process may be carried out in the manner shown at 5 Fig. 3. In this case only one partition W is employed. The potassium lye formed rises gradually in chambers 1 and 2. The separating-layer is formed by the layer of salt solution not yet decomposed and rising in the 10 chamber 2. This layer or neutral zone may be isolated when it is required to stop the process by laterally sliding doors or partitions V V', and during the process fresh solution is conducted to the same by the inlet o. 15 *a a'* are two overflow-siphons for the corresponding layers. The direction in which the layers increase is represented by arrows in all the figures.

Straight partitions are common to all the 20 forms of apparatus for carrying out the process, as illustrated in Figs. 1 to 3, said partitions being vertically arranged and being impervious to the fluid and to the electric current. The partitions do not extend through- 25 out the depth of the apparatus or of the liquid, but either begin below the level of the same or do not reach to the bottom. The distance at which the partitions are arranged from the bottom or from the level of the liq- 30 uid must be so chosen as to prevent the lines of current from being narrowed at the points where the said current passes from one compartment of the apparatus to the next. The parallel partitions have the effect that the 35 section of the liquid remains constant at all points. A contraction of the lines of current would cause whirls and agitation of the liquid, which would disturb the formation of layers. Two points are of the greatest im- 40 portance in order to retain the layers in their proper positions, viz: first, the entire omission of diaphragms of any description which might fill out the longitudinal or transverse section of a cell and enable the exchange of 45 liquid from one cell to the other by endosmosis; second, the horizontal position of the electrodes with regard to each other and the arrangement of the same in different vertical planes. By this arrangement the gases ris- 50 ing from the electrodes are forced to pass through those columns of liquid only which do not form a conducting connection between the electrodes. Furthermore, this arrange- 55 ment prevents any disturbance of the layers which could arise from the varying specific weights of the products of decomposition.

The present process may be advantageously employed for treating all kinds of artificial and natural brine, for electrolyzing Stassfurt 60 saline deposits, (the alkaline earths are precipitated in this case as hydroxids,) and generally for treating all kinds of soluble salts. The process further enables the production of acids, such as nitric acid, by electrolyz- 65 ing saltpeter, sulfuric acid from sulfates, hy-

drochloric acid from an electrolyzed mixture of chlorids and sulfates by distillation.

If mineral anodes are employed, the minerals can be brought to solution by means of the present process. 70

The process may also be employed for purifying many substances and for separating out certain substances from mixtures, thus, for instance, for purifying iron or copper salts, waste lyes containing sulfid, syrups, 75 as also for electrolyzing organic substances, in which the reducing or oxidizing powers of the electric current are employed at one electrode.

I do not limit myself to the above specified 80 decompositions, but intend to use this process in all kinds of electrolytical decompositions in which layers of differing chemical constitution are formed.

I claim as my invention—

1. A process for electrolyzing chemical compounds and gaining the products of decomposition produced by the electrolysis which consists in filling an electrolytic cell, the passage of the current through which, from the 90 anode to the cathode, is free from obstruction, by a porous diaphragm with the salt solution to be decomposed, allowing the chemically- 95 different layers formed by the electrolysis to remain undisturbed and unaltered as long as the current is passing through the cell, then feeding fresh solution to the intermediate unde- 100 composed layer of salt solution, which should be retained at a certain depth, and withdrawing the uppermost and lowermost 100 layers of decomposed products at a point outside the influence of the path of the current, in such proportion as to retain a predetermined position of the respective layers and at the close of the electrolysis dividing the 105 layers by means of interposed partitions said partitions being mechanically impervious to the liquid substantially as described.

2. A process for electrolyzing chemical compounds, which consists in first producing in 110 an electric cell, the passage of the current through which, from the anode to the cathode is free from obstruction by a porous dia- 115 phragm, a layer of non-decomposed solution, passing an electric current through the cell 115 and allowing a layer of the respective com- 120 ponents into which the said solution is de- composed to form, one above and one below the said non-decomposed layer feeding fresh solution to the latter layer and withdrawing the decomposed anodic and cathodic solutions in such proportions as to retain approxi- 125 mately unaltered the layers formed by the electrolysis and finally at the close of the elec- 130 trolysis substituting an actual mechanical partition for the non-decomposed layer, sub- stantially as described.

3. The combination of a receptacle having a series of vertical partitions, arranged as regards the interior of the vessel or receptacle 130

so as to allow the passage of the liquid above or below the said partition-walls, horizontally-disposed electrodes, arranged in different vertical planes, a feed-pipe at a point between 5 said electrodes for the fresh solution and outlet-pipes above and below said electrodes for the decomposed layers said feed and outlet pipes having spray-heads, and means for

passing the current to the electrodes substantially as described.

In witness whereof I have hereunto set my hand in presence of two witnesses.

WILLY BEIN.
